CLAIM

The ornamental design for a demolition tool, as shown and described.

DESCRIPTIONFIG. 1 is a perspective view of the demolition tool;
FIG. 2 is a side view thereof, the opposite side being a mirror image;

FIG. 3 is a top view thereof;

FIG. 4 is a bottom view thereof;

FIG. 5 is a first end view thereof; and,

FIG. 6 is a second end view thereof.

The broken lines in the drawings illustrate a portion of the demolition tool that forms no part of the claim.
